UNITED STATES PATENT OFFICE

146,519

DESIGN FOR A PLATTER OR SIMILAR ARTICLE

Alfred Faustin Ramsthal, West Bend, Wis., assignor to West Bend Aluminum Company, West Bend, Wis., a corporation of Wisconsin

Application January 31, 1946, Serial No. 126,126

Term of patent 14 years

(Cl. D44—15)

To all whom it may concern:

Be it known that I, Alfred Faustin Ramsthal, a citizen of the United States, residing at West Bend, in the county of Washington and State of Wisconsin, have invented a new, original, and ornamental Design for a Platter or Similar Article, of which the following is a specification, reference being had to the accompanying drawing, forming a part thereof, and in which:

I claim:

The ornamental design for a platter or similar article, as shown.

ALFRED FAUSTIN RAMSTHAL.
